UNITED STATES PATENT OFFICE.

JAMES H. BOYE, OF CHICAGO, ILLINOIS, ASSIGNOR TO JAMES H. BOYE MANUFACTURING COMPANY, OF CHICAGO, ILLINOIS, A CORPORATION OF ILLINOIS.

COMMODITY-CABINET.

1,294,761.

Specification of Letters Patent. Patented Feb. 18, 1919.

Application filed July 1, 1918. Serial No. 242,851.

To all whom it may concern:

Be it known that I, JAMES H. BOYE, a citizen of the United States, residing at Chicago, in the county of Cook and State of Illinois, have invented certain new and useful Improvements in Commodity-Cabinets, of which the following is a specification.

This invention relates to commodity cabinets for use by merchants and dealers in storing various small articles of merchandise in a manner to enable them to be readily accessible to the merchant in making sales and to prevent confusion and loss of time in the finding of small articles. While the invention has been more particularly designed to facilitate the retail handling of sewing machine accessories, such as needles, bobbins, shuttles, and the like, yet it is readily adaptable without change of structural principle, to the handling of supplies, accessories and small parts of other machines, and hence in its broader aspects is not limited to a commodity cabinet for sewing machine parts and accessories.

The main and general object of this invention is to improve commodity cabinets of this general type more particularly in the direction of enlarging or widening the field or scope of usefulness of such devices as a means of enabling the owners of individual machines to locate the source or sources of manufacture of such machines so that the correct renewal or repair parts may be readily obtained either from the cabinet itself or from the manufacturer.

It is well known that in this country there are many hundreds of differently named sewing machines in general use, commonly known as "stenciled" machines, and each adapted to employ one or another of a quite limited number of standard sewing-machine needles, bobbins, shuttles, etc.; and usually the name of the machine gives no indication of the source of manufacture of these parts.

Although there are comparatively few manufacturers of sewing machines, yet many thousands of such machines are sold each year which bear the name or trade-mark of the dealer, and not the name of the manufacturer. Consequently when the owner or user of a certain "stenciled" machine desires to purchase the proper needle, or some other accessory, to be used therein, the vendor of such accessories very often does not know the size or shape of the particular accessory

required by the buyer, this condition causing annoyance and delay to both the purchaser and the vendor. An object of the invention, therefore, is to provide in association with the cabinet improved instrumentalities by which the needle or other accessory of any one of a large number of machines going under different names may be at once located and found in the cabinet.

Again, certain of these many differently named machines are constantly dropping out of the market or becoming obsolete under their particular names, although the machines themselves are still being manufactured and sold under other and different names. Another object of the invention is to provide in association with the cabinet an instrumentality whereby the user of such an obsolete machine may be able to locate in and obtain from the cabinet a needle carried by the cabinet that will fit that particular machine.

Another object of the invention is to provide instrumentalities by which the source of manufacture of parts or accessories not commonly carried in stock and sold by the retail dealer from the cabinet itself may be readily ascertained as a preliminary to ordering such parts from the factory. This feature of the invention, as will hereinafter appear in detail, is based on the fact that the presser feet of all of the limited number of machines issuing from different factories present slight differences in size and shape.

Another object is to provide, in a cabinet adapted to vend hand sewing needles, an instrumentality whereby the location of different sizes of such needles, both straight and assorted, may be readily determined and mistakes and confusion resulting from the wrong selection or replacement of the needle packages in the carrier of the cabinet avoided.

Another object is to provide an improved construction of commodity carrier and casting therefor which shall facilitate the withdrawal and replacement of the goods by affording a more convenient access to the latter, as compared with commodity cabinets of this general type heretofore known.

Still other useful purposes served by the invention will be apparent to those skilled in the art from the following detailed description of one practical and preferred embodiment thereof which I have illustrated

in the accompanying drawings; it being borne in mind that the device of the invention is designed to serve not only as a storing and vending cabinet to contain in proper order, and to facilitate the dispensing of, small articles such as sewing machine accessories, but also as a guide and cyclopedia of useful information relating to sources of manufacture not only of the specific articles carried by the cabinet, but also of other machine parts emanating from the same sources of manufacture, thereby dispensing largely with the necessity of the large illustrated catalogues of parts published and distributed to retail dealers by the different manufacturers.

In the accompanying drawings,—

Figure 1 is a top plan view of the cabinet;

Fig. 2 is a front elevation, as viewed from the lower side of Fig. 1;

Fig. 3 is a horizontal or plan section just below the plane of the top wall of the casing;

Fig. 4 is a detail vertical section substantially on the line 4—4 of Fig. 1;

Fig. 5 is a fragmentary vertical section on the line 5—5 of Fig. 3, showing the manner of hinging the commodity receptacles on the carrier frame; and

Fig. 6 is a detail top plan view of the actuating arm of the carrier, with which are associated the locking pawl and a pair of pointers that coöperate with arcuate indexes on the top wall of the casing.

Referring to the drawings, 10 designates the top wall and 11 the side wall of a substantially circular sheet metal casing, the same being formed with four integral hollow legs 12 by which the cabinet rests on a counter or table. In the front portion of the side wall 11, midway between adjacent legs 12, is formed a rectangular opening 13, the top and sides of which are preferably equipped with a stiffening border frame 14. Secured to the upper side of the top wall 10 and extending diametrically from front to rear thereof is a stiffening plate or strip 15 formed with a widened substantially circular central portion 15', as clearly shown in Fig. 1.

Strongly secured to and centrally of the under side of the top wall 10 of the casing, as by screw-bolts 16, is a circular plate 17 (Fig. 4) which serves as an auxiliary stiffener to the top wall 10 and also as a base-plate for a depending spindle or post 18 integral therewith or rigidly secured thereto. Mounted to turn on this spindle 18 is the hub 19 of a carrier frame comprising four radially extending arms or spokes 20 (Fig. 3) that reach nearly to the circular side wall 11 of the casing; the hub 19 being removably supported in position on the spindle 18 by a nut 21 and lock-nut 22.

On the outer ends of the arms 20 are mounted vertical posts 23, on which are hinged four generally sector-shaped pan-like commodity receptacles or holders. Describing these receptacles, which are all alike, each has a solid bottom wall 24 (Fig. 5) an outer or front wall 25 having the same curvature as, and lying just inside, the side wall 11 of the casing, and a somewhat lower curved inner or rear wall 26. This rear wall 26 is provided centrally thereof with a vertical indentation or notch 27 for a purpose hereinafter disclosed. A certain inner portion of the receptacle is partitioned to form rectangular containers 28 adapted to hold packages of straight and assorted sizes of ordinary hand sewing needles, and across the remaining space of the receptacle, at a suitable distance above and parallel with the bottom 24, extends a plate 29 that is formed with numerous circular apertures or holes 30 and 31 of different sizes to receive and support in upright position the circular tube-like boxes in which sewing machine needles, bobbins, shuttles, and like small parts are usually packaged for the trade. It will be observed that each complete receptacle is symmetrically constructed with reference to its median radial line or axis, so that each receptacle is in effect a double-compartment affair, each compartment being designed to hold the goods of a single manufacturer.

Each twin compartment receptacle is pivoted on the hinge post or pin 23 in the manner clearly shown in Fig. 5, wherein it will be observed that the post 23 passes through a hole in the bottom wall 24 and also through a hole in a hinge-lug 32 that extends inwardly of the upper end of a vertical strip 33 that is secured to the outer side of the wall 25 of the receptacle, centrally of said wall. This strip 33 is also formed with outwardly offset vertical lips or flanges 34 that, with similar lips or flanges 35 formed on vertical strips 36 secured to the ends of the wall 25, constitute slideways to removably support a card 37 on which is printed the name of a manufacturer and an alphabetical or other symbol by which said manufacturer is identified on certain indexes hereinafter described. This card or chart also preferably has printed thereon cuts of various small machine parts not carried by the cabinet, with their factory numbers, pertaining to the particular manufactory identified by the card or chart. On the outer edge of the strip 36 is formed a finger-hold 38 by which that half of the receptacle, containing one of the twin compartments, can be swung outwardly through the opening 13, as indicated by dotted lines in Fig. 3. On the lower edge of the front wall 25 are a pair of depending lugs 39, one on each side of the pivot post 23. When one half of

the receptacle is drawn out, the other half of course swings inwardly, and its lug 39 strikes the carrier arm 20, thus forming a stop to limit the outward swinging movement. On the inner side of the casing wall 11 are secured stops 40 (Fig. 3) located at a suitable distance back of the sides of the opening 13 to arrest the inward swinging movement of the receptacle at its correct normal position. Attached to the hub 19 of the carrier are four radially extending elastic arms 41 terminating in rounded heads 42 that normally engage the notches 27 and center the receptacles within the casing so that the carrier may turn in the latter. When any individual receptacle is swung outwardly or inwardly of the casing, the arm 41 bends, and the head 42 slides over the wall 26, acting as sort of drag to steady the movement.

Referring next to the means for actuating the carrier frame so as to bring any one of the eight compartments opposite the casing opening, 43 designates a pinion fast on the upper end of the carrier hub 19 (Fig. 4). With this pinion meshes a gear 44 that is fast on the lower end of a short shaft 45 that is journaled in the top wall 10 and its stiffening plate 15'. Fast on shaft 45, just above the plate 15', is a radial actuating arm 46 (Figs. 4 and 6) on the free end of which is an upstanding finger-hold 47. On the free end of arm 46 is also formed a forwardly directed pointer finger 48, and in rear of the latter is an upwardly offset rearwardly directed pointer finger 49. Secured to the stiffening plate 15 is a segment-plate 50 that overlies all except the free end and pointers of the arm 46. This segment-plate is formed with shoulders or stops 51 (Fig. 1) that limit the swinging movements of the arm 46 and, between said stops, with a series of equally spaced notches 52 in its raised edge. These notches are engaged by a spring-pressed manually retractable locking dog or pawl 53 mounted on the finger-hold 47. The locking notches 52 correspond in number with the commodity compartments of the carrier (eight being here shown). The name cards or charts 37 of the eight compartments bear the identifying symbols A to H inclusive; and on the stiffening plate 15', opposite the free edge of the segment plate 50, is a corresponding index consisting of the letters A to H inclusive grouped in arcuate form opposite the locking notches 52. When the actuating arm is swung to carry the pointer 48 opposite any letter of this index, the correspondingly identified carrier compartment is brought opposite the opening 13 and may be swung on its individual hinge outwardly through the latter to afford easy access to the goods which it contains. At the same time, this compartment is held in delivery position at the

opening 13 by the dog 53 which locks the carrier frame against turning.

On the free edge of segment plate 50 are two indexes of hand needles carried by the several compartments, one index showing straight sizes (1 to 10 inclusive) and the other showing assorted sizes. The pointer 49 cooperates with these indexes in the same way that the pointer 48 cooperates with the alphabetical index A to H inclusive.

As hereinabove mentioned, there are in the sewing machine industry, a limited number of makers of different machines (eight being assumed in the present case), and there are many hundreds of machines going under as many different dealers' names, and all manufactured by this limited number of makers. Hence, a customer may go to her dealer to buy a needle, bobbin, shuttle, or other accessory for her sewing machine, giving him the name of her machine, and he, not knowing the factory source of that particular machine, may be at a loss to supply her with a part that will fit. My present invention provides a ready means for enabling the dealer to instantly ascertain the factory source. On the top wall 10 of the casing is provided an extensive alphabetical name index of all the principal and most extensively used machines put out by various dealers under their own names. This index may conveniently be arranged in curved concentrically grouped columns 54, as shown in Fig. 1. On one side of each column 54 is a column 55 containing the same receptacle-identifying symbols, comprising the letters A to H inclusive, that are employed in the central index with which the pointer 48 is associated. To illustrate, let it be assumed that a customer calls for a needle to fit her "Advance" machine. The dealer finds the letter D opposite the name "Advance" in the index columns 54 and 55. He then swings the actuating arm 46 until its pointer 48 points to D of the central index. This brings the D compartment of the carrier receptacles opposite the opening 13 (see Fig. 2), and in this compartment will be found the correct needle for the "Advance" machine. The chart 37 of this compartment also discloses the fact that the "Advance" machine is a product of the Davis Sewing Machine Company.

If a package of hand needles, size 3 or 6, is desired, the arm 26 is swung to bring the pointer 49 to the correspondingly marked position of the index on the free edge of segment-plate 50. This brings the C compartment opposite the opening 13, and in one of the containers 28 of this compartment will be found packages of hand needles of the required size.

In the great majority of cases, the correct sewing machine needle or other accessory carried by the cabinet can be located in this

way. It may sometimes happen, however, that a needle or other part pertaining to a machine not listed in the name index is called for. In the case of needles, this can be located in either of two ways. On the upper face of segment-plate 50 is a needle chart consisting of radially arranged exact size prints 56, 57, 58 and 59 of the outer (point and eye portions) of all the different 5 sewing machine needles made by the different makers. Since substantially the same needle is sometimes used by two or more makers, this list is smaller than the list of makers. The shaft 45 extends upwardly 10 through the segment-plate 50 (Fig. 4), and fast on its upper end is a radial arm 60, the upper surface of which is channeled to support the shank of a sewing machine needle laid therein. If the customer can produce a 15 sample needle that fits her machine, this needle is laid on the arm 60 with its shank end abutting against the inner end of the channel, and the arm 26 is turned until the overhanging point and eye portion of the needle 20 exactly registers with and matches one of the chart prints 56, 57, 58 or 59. This brings to the opening 13 a carrier receptacle containing needles identical with the sample.

But it might happen that the owner of a 25 machine not listed on the name index (because the machine under that particular name had been discontinued on the market or for any other reason) had no sample needle; or it might be that she desired to order 30 from the factory some machine part, not carried in stock by the cabinet. My invention takes care of these situations also. Practically all of the different makes of sewing machines that go into the hands of domestic 35 consumers have detachable presser feet with bifurcated or forked shanks; but it is a somewhat curious fact that all of these forked shanks differ in specific size and shape. My invention utilizes this structural 40 peculiarity in the following way: In the top surface of the stiffening-plate 15' I form a series of die impressions 61, 62, 63, 64, 65, 66, 67 and 68 of the forked shanks of all the different makes of presser-feet, these 45 impressions being grouped in arcuate form outside of and opposite the alphabetical index A to H inclusive, in the manner clearly shown in Fig. 1. The customer brings to the store the presser-foot of her machine. 50 The dealer applies it to the various dies, and finds, for example, that it fits the die 64 which is opposite the D symbol of the compartment-identifying index. The pointer 48 is swung to that point, and the 55 presser-foot is thus identified as belonging to a Davis make of machine. Hence, a needle or other part carried by the cabinet that may be desired is readily obtained from the D compartment of the commodity carrier. 60 Or if some one of the small parts shown and

identified by its number on the pictorial chart 37 of the D compartment and not contained in the cabinet is desired, the dealer knows that the Davis factory is the manufacturing source of that particular 70 part, and no time need be lost in hunting through a lot of illustrated makers' catalogues to ascertain where to send an order.

It will thus be seen that my present invention provides not only a handy and convenient cabinet for storing in order and facilitating the vending of small machine parts and accessories, but it also has the character of a practically complete and universal cyclopedia by means of which the 80 manufacturing source of any customer's machine may be quickly ascertained. In its structural details and relative arrangement of parts the device may, of course, be considerably varied from the embodiment of 85 the invention herein shown and described, without departing from the principles involved or sacrificing any of the utilities and advantages obtained. Hence, I reserve all such changes, modifications and equivalents as fall within the spirit and purview 90 of the appended claims.

I claim:

1. In a commodity cabinet, the combination of a casing having top and side walls, 95 a spindle rigidly secured to and depending from the under side of said top wall, a carrier having a hub journaled on said spindle, a pinion fast on said hub, a shaft journaled in said top wall, a gear fast on said shaft and meshing with said pinion, and an operating arm fast on said shaft above said top wall.

2. In a commodity cabinet, the combination of a casing having a side wall formed 105 with an opening, a carrier frame pivotally mounted in said casing and having a plurality of radial arms, and a corresponding plurality of pan-like receptacles pivoted centrally of their outer sides on the outer ends 110 of said arms, either half of each receptacle when brought opposite said opening being adapted to swing outwardly therethrough.

3. In a commodity cabinet, the combination of a casing having a side wall formed 115 with an opening, a carrier frame pivotally mounted in said casing and having a plurality of radial arms, a corresponding plurality of symmetrical and generally sector-shaped receptacles having curved and centrally, 120 notched inner sides pivoted centrally of their outer sides on the outer ends of said arms, either half of each receptacle when brought opposite said opening being adapted to swing outwardly therethrough, means for 125 limiting the swinging movements of said receptacles, and yieldable elastic detents normally engaging the notches of the inner sides of said receptacles to center the latter in said casing.

4. In a commodity cabinet, the combination of a casing having top and side walls and an opening, a carrier having a plurality of commodity receptacles and mounted to oscillate in said casing to bring any of said receptacles opposite said opening, a pinion on said carrier, a gear journaled in said casing and meshing with said pinion, a radial actuating arm for said gear, an arc-shaped carrier-receptacle index on the top wall of said casing concentric with the axis of said gear, and a pointer on said actuating arm cooperating with said index. 55
5. In a commodity cabinet, the combination of a casing having top and side walls and an opening, a carrier having a plurality of commodity receptacles and mounted to turn in said casing to bring any of said receptacles opposite said opening, means, including a swinging arm, for turning said carrier, an arc-shaped carrier-receptacle index on the top wall of said casing concentric with the pivotal axis of said swinging arm, a pointer on said arm coöperating with said index, a locking pawl carried by said arm, and a segment plate coöperating with said pawl. 60
6. In a commodity cabinet, the combination of a casing having top and side walls and an opening, a carrier having a plurality of commodity receptacles and mounted to oscillate in said casing to bring any of said receptacles opposite said opening, a pinion on said carrier, a gear journaled in the top wall of said casing and meshing with said pinion, a radial actuating arm for said gear, an arc-shaped carrier-receptacle index on the top wall of said casing concentric with the axis of said gear, a pointer on said arm co-operating with said index, a locking pawl carried by said arm, and a segment-plate having marginal notches coöperating with said pawl to lock said arm with its pointer opposite any one of the index characters. 65
7. In a sewing-machine commodity cabinet, the combination of a casing having top and side walls and an opening, a carrier having a plurality of needle receptacles and mounted to turn in said casing to bring any of said receptacles opposite said opening, means, including a vertical shaft journaled in the top wall of the casing, for turning said carrier, a needle chart in arcuate form on said top wall and concentric with the axis of said shaft, and a radial arm mounted on said shaft and formed with a needle-supporting groove in its upper side. 70
8. In a sewing machine commodity cabinet, the combination of a casing having top and side walls and an opening, a carrier having a plurality of parts receptacles and mounted to turn in said casing to bring any of said receptacles opposite said opening, means, including a manually operated arm, for turning said carrier, a die-plate on the top wall of said casing containing a row of presser-foot impressions representing respectively as many different makes of machines, and a pointer carried by said arm and co-operating with said impressions. 75
9. In a sewing machine commodity cabinet, the combination of a casing having top and side walls and an opening, a carrier having a plurality of parts receptacles and mounted to turn in said casing to bring any of said receptacles opposite said opening, means, including a swinging arm, for turning said carrier, a die-plate on the top wall of said casing containing an arcuate row of presser-foot impressions concentric with the pivotal axis of said arm and representing respectively as many different makes of machines, and a pointer on the free end of said arm coöperating with said impressions. 80
10. In a sewing machine commodity cabinet, the combination of a casing having top and side walls and an opening, a carrier having a plurality of parts receptacles and mounted to turn in said casing to bring any of said receptacles opposite said opening, means, including a manually operated arm, for turning said carrier, a die-plate on the top wall of said casing containing a row of presser-foot impressions representing respectively as many different makes of machines, a pointer carried by said arm and movable with the latter along said row of impressions, and a chart mounted on each of said receptacles and visible through said opening when the receptacle is brought opposite the latter, said chart disclosing the manufacturing source of the machine to which any presser-foot indicated by said pointer and die-index belongs. 85 90 95 100

JAMES H. BOYE.
